FIG. 1

FIGURE 1 is a perspective view of a magnetic tape recorder resting in one operating position showing one embodiment of my new design.

FIGURE 2 is a perspective view of the tape recorder shown in FIGURE 1 resting in another operating position.

FIGURE 3 is a side elevation, drawn on an enlarged scale, of the tape recorder shown in the position of FIGURE 1, the opposite side being substantially a mirror image thereof.

FIGURE 4 is a rear elevation, drawn on an enlarged scale, of the tape recorder resting in the position shown in FIGURE 2.

FIGURE 5 is a rear elevation, drawn on an enlarged scale, of the tape recorder resting in the position shown in FIGURES 1 and 3.

FIGURE 6 is a perspective view of a magnetic tape recorder resting in one operating position showing another embodiment of my new design.

FIGURE 7 is a perspective view of the tape recorder shown in FIGURE 6 resting in another operating position.

FIGURE 8 is a side elevation, drawn on an enlarged scale, of the tape recorder shown in the position of FIGURE 6, the opposite side being substantially a mirror image thereof.

FIGURE 9 is a rear elevation of the tape recorder resting in the position shown in FIGURES 6 and 8.

FIGURE 10 is a rear elevation, drawn on an enlarged scale, of the tape recorder resting in the position shown in FIGURE 6.

The tape reel shown in broken lines in FIGURES 6, 7 and 8 is for illustrative purposes only.

This application is a continuation-in-part of my two copending design applications, Serial Numbers D80,870 and D80,871, both filed July 14, 1964, and now abandoned.

I claim:

The ornamental design for a tape recorder, substantially as shown and described.
